CLAIM

The ornamental design for a display screen with graphical user interface of a gaming machine as shown and described.

DESCRIPTION

The FIGURE is a front view of a display screen with graphical user interface of a gaming machine showing our new design.

The peripheral broken line represents a boundary of the display screen with graphical user interface and forms no part of the claimed design. The broken lines depicting the remainder of the display screen with graphical user interface of a gaming machine form no part of the claimed design.
